UNITED STATES PATENT OFFICE.

WILLIAM A. LORENZ, OF HARTFORD, CONNECTICUT; ASSIGNOR TO THE OTAKA FABRIC COMPANY, OF HARTFORD, CONNECTICUT, A CORPORATION OF CONNECTICUT.

PAPER HAT.

Application filed July 8, 1920. Serial No. 384,729.

To all whom it may concern:

Be it known that I, WILLIAM A. LORENZ, a citizen of the United States, residing in Hartford, in the county of Hartford and 5 State of Connecticut, have invented certain new and useful Improvements in Paper Hats, of which the following is a specification.

This invention relates to various steps in 10 the manufacture of hats, of which there is selected for illustration the usual form of men's straw hats.

One of the objects of the invention is to 15 reduce the cost of production of braided hats, to lighten the weight of the hat, to increase its durability and resistance to ageing, and to enhance its appearance.

For the material of the hat, there is employed paper, which may be manila or other 20 tough paper, to make a hat which is light as compared to an ordinary straw hat, and which will successfully withstand exposure to rain and sunlight, and hard usage, and may be produced at relatively low cost.

25 To form the strand or strands which are sewed together to form the body of the hat, the paper is preferably folded longitudinally to give the strand thickness and strength. The paper is preferably so folded that the 30 strand has three plies, so that both edges of the strand are folded edges, thus conducting to the neatness, strength and durability of the hat, as well as facilitating the stitching of strand to strand; one edge of 35 the original ribbon of paper being turned within a fold of the strand, and the other edge of the original ribbon or band being also concealed, as it is arranged to go on the inner or under side of the strand or 40 braid as it is stitched into place to form the hat.

After the paper is folded up to form the strand, it is formed into longitudinal 45 grooves, which gather the strand widthwise; and it is also crinkled transversely to gather the strand lengthwise, the crinkles being formed throughout the corrugations or flutes, and having a zigzag arrangement across the strand, which is therefore yieldable in all directions, thus well adapting it 50 for coiling upon itself edgewise to form the top and brim of the hat. The expansibility of the braid or strand also conduces to a long life of the hat, since when rough-

ly handled it is adapted to yield and is not 55 liable to break. The flexibility and suppleness of the strands also adapt the paper hat to fit the head of the wearer comfortably, thus constituting an improvement upon the common rigid straw hat. The paper may 60 be preferably water-proof and colored or otherwise treated, and may be blocked and pressed into the desired shape. Notwithstanding its superiority, it can be manufactured at low cost. 65

Other features and advantages will hereinafter appear.

In the accompanying drawings,

70 Figure 1 represents a portion of an original band of plain paper.

Figure 2 is a plan, and Figure 3 an edge view of a portion of strand or braid which is formed by folding over each other the opposite side portions of the original band seen at Figure 1. 75

Figure 4 illustrates, on a somewhat enlarged scale, the Figure 2 strand, after it has been gathered both transversely and longitudinally. While for this purpose the flutes and crinkles may be formed in the 80 strand after the latter is folded, as at Figure 2, still it is within the scope of the invention to flute and crinkle or otherwise form a combined gathering in the original band at Figure 1 before folding it. The 85 Figure 4 method is preferred, because the flutes and crinkles in the different plies fit into each other, being made by one operation, as set forth in my co-pending application No. 346,310, filed December 20, 90 1919.

Figure 5 illustrates a strand or braid, the plies of which have been pasted together; the braid being preferably formed with transverse creases, each crease being V-shaped, and alternate creases pointing in opposite directions, to facilitate the coiling of the strand edgewise to form the nucleus and the surrounding portions of the coil which make the top of the hat, seen at Figure 8. 95

Figure 6 is a plan of a three-ply braid or strand having a design which is produced by suitably-formed rolls.

Figure 7 shows diagrammatically the 105 method of embossing the Figure 6 configuration upon the Figure 5 strand, by means of embossing rolls or dies.

Figure 8 is a plan, and Figure 9 an edge view of one form of hat embodying the present improvements.

The original strip, band or web 10, at 6 Figure 1, may be folded along its opposite sides at the lines marked 11, 12 so that one fold falls within the other, as at Figure 3, thus making a three-ply strand or braid of paper. At Figure 2, lines 13, 14, indicate 10 the side edges of the original band 10. The plies of this braid are preferably pasted together throughout their length, as indicated diagrammatically by the strip portion 15 at Figure 2. The braid thus formed may be 15 passed through a gathering machine of the type disclosed in said application, and thereby formed with longitudinal depressions 16 and elevations 17, making flutings or corrugations, and these may at the same 20 time be transversely crinkled as at 18, so that the strand is gathered both longitudinally and laterally; the crinkles having zigzag arrangement across the strand, which is 25 yieldable or stretchable both laterally and longitudinally. By this means a substantial, durable and yieldable strand or braid is cheaply formed of inexpensive paper, of which an ample supply is available.

The initial length or portion of the strand 30 seen at Figure 4 is then formed with transverse creases 19, at suitable intervals, to render the beginning of the strand still more capable of being turned edgewise forming the nucleus 20 of the hat top. These creases 35 may be narrow and V-shaped, and may point alternately in opposite directions, as at Figure 5; those upon the outer edge of the winding strand being formed for opening out, while those upon the opposite or inner edge 40 may be formed for closing up, with the result seen diagrammatically in the coiled nucleus at Figures 5 and 8. After the nucleus is made, the coiling may continue, and the contiguous side edges of the braid may be 45 stitched together to form the top, sides and brim of the hat, as at 21, Figure 8; the paper being sufficiently flexible edgewise to enable it to perform the required coiling without carrying the creases 19 along the braid after 50 the nucleus portion is formed.

After the hat is stitched roughly into form, and a hem 22 stitched upon the outer edge of the brim, preferably by folding over the outermost whorl of the braid, the 55 hat may be pressed into final shape by means that are well known in the manufacture of straw and other hats; and glue or other stiffening material may be used to conduce to the permanence of the shape of the hat. 60 The paper which forms the hat may be of any desired color, and may be protected by any suitable means against damage from moisture.

A modified method of gathering the paper 65 is illustrated at Figures 6 and 7, in which a

pair of embossing rolls 23, 24 are engraved or shaped to emboss the strand 25 for the sheet 13 from which it is folded up, as indicated at 26, the embossing having the appearance of wickerwork, which is arranged on the bias or diagonally of the strip. This makes the paper yieldable in all directions, since it is crinkled in zigzag arrangement throughout, and it is desirable for a hat braid because of its resemblance to woven 75 material.

In forming the Figure 6 braid or strand, the folded material is preferably first corrugated and transversely crimped, as at Figure 4, and then passed between the figured embossing rolls 23, 24, and thereby embossed to great depth, Figure 6, to give the desired wickerwork configuration to the braid. The preliminary treatment of the braid, as seen at Figure 4, renders the braid elastic or 80 yieldable in all directions, so that it may be then embossed deeply to secure the desired appearance and to avoid liability of subsequent tearing of the paper.

If desired, the paper may be gathered 85 longitudinally and laterally by the preliminary corrugating and crinkling operations while the paper is in the unfolded condition at Figure 4. Then it may be folded to form a braid at Figure 4, which may then be embossed, as at Figure 6.

Variations may be resorted to within the scope of the invention, and portions of the improvements may be used without others.

Having thus described my invention, I 100 claim:

1. A strand formed of a strip of paper which is folded to form three plies, one of said plies being turned in between the other two and pasted in position, said strip being 105 crinkled or gathered to render it edgewise flexible.

2. A strand formed of a strip of paper which is longitudinally folded to form three plies, said plies being pasted together and 110 being gathered by longitudinal corrugations and transverse crinkles.

3. A strand formed of a strip of paper which is longitudinally folded to form three plies, said plies being pasted together and 115 being gathered by longitudinal corrugations and transverse crinkles, the crinkles extending in a zigzag arrangement across the strand, which is yieldable in all directions.

4. A strand formed of a strip of paper which is longitudinally folded to form three plies, said plies being gathered by longitudinal corrugations and transverse crinkles, the crinkles extending in a zigzag arrangement across the strand, which is yieldable in all 120 directions, said strand additionally having transverse creases 19 to facilitate edgewise coiling thereof, said creases distinct from said crinkles.

5. A strand formed of a strip of paper 130

- which is longitudinally folded to form superposed plies, said plies being gathered by crinkles extending across the strand, which is yieldable in all directions, said strand additionally having transverse creases 19 to facilitate edgewise coiling thereof, the creases being V-shaped and pointing in opposite directions, and being distinct from said crinkles.
10. A paper strand longitudinally folded to form superposed plies and embossed deeply in a manner to render it yieldable in all directions.
7. A paper strand having therein corrugations crossed by crinkles upon which is imposed an embossed design.
8. A paper strand longitudinally folded and deeply embossed, the embossing being imposed upon crinkles previously made in the strand.
9. The method of forming a strand, comprising folding a strip of paper longitudinally to make a three-ply strand, pasting the plies together, and passing the strand 25 through a gathering machine to form longitudinal flutings or corrugations and transversely crinkling the same, whereby the strand is gathered both longitudinally and laterally and made yieldable in all directions.
30. The method of forming a strand, comprising folding a strip of paper longitudinally to make a three-ply strand, pasting the plies together, passing the strand through a gathering machine to form flutings or corrugations and transversely crinkling the same, whereby the strand is gathered both longitudinally and laterally and made yieldable in all directions, and embossing the corrugated and crinkled strand.
11. The method of forming a strand, comprising folding a strip of paper longitudinally to make a three-ply strand, pasting the plies together, passing the strand through a gathering machine to form flutings or corrugations and transversely crinkling the same, whereby the strand is gathered both longitudinally and laterally and made yieldable in all directions, and forming a portion of the strand with transverse creases to aid in forming the nucleus of the hat top.
12. The method of forming a strand, comprising folding a strip of paper longitudinally to make a three-ply strand, pasting the plies together, passing the strand through a gathering machine to form flutings or corrugations and transversely crinkling the same, whereby the strand is gathered both longitudinally and laterally and made yieldable in all directions, and forming the strand with transverse creases to aid in forming the nucleus of the hat top, said creases being V-shaped and pointing in opposite directions.
13. A longitudinally folded three-ply strand of paper, the plies being pasted together and gathered longitudinally and laterally.
14. A longitudinally folded three-ply strand of paper, the plies being pasted together and gathered longitudinally and laterally, by longitudinal corrugations and transverse crinkles, the crinkles having zig-zag arrangement across the strand, said strand also having distinct transverse creases 75 for the purposes specified.
15. The method of forming a paper strand, consisting of first folding it longitudinally, then crinkling the same to render it yieldable, and then subjecting it to an embossing 80 operation.
16. The method of folding a web of paper longitudinally to make a three-ply strip, and then forming longitudinal grooves and transverse crinkles in the strip through the plies thereof.
17. The method of folding a web of paper longitudinally to make a three-ply strip, and then embossing or crinkling the folded strip to render it flexible throughout.
